BOBBIN

Joseph Cavanaugh, Barrington, N. J.

Application March 27, 1941, Serial No. 385,543

4 Claims. (Cl. 242—125)

This invention relates to an improvement in bobbins, and more particularly to an improved construction of bobbin spindle by means of which the thread may be readily attached to the spindle to prevent the thread from slipping relatively to the bobbin spindle during the initial stages in the winding of the thread on the bobbin.

More particularly, it is an aim of the invention to provide a spindle having an annular outwardly opening groove having circumferentially spaced portions of different widths, adjacent the periphery of the spindle, to provide wide grooved portions for readily receiving the end of a thread and more restricted grooved portions in which the thread will be wedged and held as the bobbin rotates.

Still another aim of the invention is to provide a bobbin having means for catching and holding an end of a thread to be wound thereon and by means of which the end of a thread can be effectively engaged in less than a single revolution of the bobbin.

Still a further aim of the invention is to provide means for catching and holding the end of a thread to be wound on a bobbin which is so arranged that rotation of the bobbin for winding the thread thereon will tend to direct the thread in a direction so that it will be more tightly wedged and held, whereas the rotation of the bobbin for unwinding the thread therefrom will be in a direction to cause the attached end of the thread to be readily released.

Other objects and advantages of the invention will hereinafter become more fully apparent from the following description of the drawing, which illustrates a preferred embodiment thereof, and wherein—

Figure 1 is a plan view of a bobbin constructed in accordance with the invention,

Figure 2 is a sectional view of the same, taken substantially along the plane of the line 2—2 of Figure 1,

Figure 3 is a fragmentary plan view of a portion of the bobbin spindle and on an enlarged scale, and

Figures 4 and 5 are sectional views taken substantially along the planes of the lines 4—4 and 5—5, respectively, of Figure 3.

Referring more particularly to the drawing, wherein like reference characters designate like or corresponding parts throughout the different views, 10 designates generally a bobbin including a spindle 11 which, as shown, is provided with a longitudinal bore 12 which extends therethrough. The spindle 11 is provided with externally

threaded ends 13. The bobbin 10 also includes a pair of heads 14 which are provided with centrally disposed threaded openings 15 for detachably engaging the threaded ends 13 for assembling the heads 14 on the ends of the spindle 11. The parts of the bobbin 10, previously described, are of conventional construction and are shown merely to illustrate the application of the improvements which will hereinafter be described, and said parts may therefore be varied without effecting the improvements comprising the invention.

The improvement constituting the invention comprises an annular groove, designated generally 16 which is formed in the spindle 11, intermediate of its ends, and which opens outwardly of the periphery thereof. The groove 16 is provided with spaced, substantially parallel side wall portions 17, adjacent the bed 18 of the groove 16. The upper portions of the side walls of the groove 16 are flared outwardly to form the complementary portions 19 and the complementary portions 20. As best seen in Figures 1 and 3, the complementary portions 19 are circumferentially spaced by the complementary portions 20 which in turn are circumferentially spaced by the complementary portions 19. As best seen in Figure 3, the inclination or slant of the portions 19 is less than that of the portions 20 so that said portions 19 at their upper edges, and intermediate of their ends, are spaced a substantially greater distance apart than the corresponding edges of the portions 20 to form circumferentially spaced portions 21 of the groove 16 which are substantially wider at the periphery of the spindle 11 than other portions of the groove 16. Furthermore, as best seen in Figures 4 and 5, the portions 19 extend to a greater depth in the groove 16 than do the portions 20. As seen in Figure 3, the portions 19 taper from intermediate of their ends to the ends thereof where they merge with the portions 20.

From the foregoing it will be apparent that when the bobbin 10 is revolving and the end of a thread, not shown, is applied to the bobbin the end of the thread will readily enter one of the widened portions of the groove 16 formed by the portions 19 and will be wedged between the portions 17, contiguous with the portions 20, as the bobbin 10 revolves. Furthermore, it will be apparent that the rotation of the bobbin 10 will tend to pull the end of the thread toward the bed 18 of the groove 16 wherein it will be most effectively held. In unwinding the thread from the bobbin 10 it will be obvious that the direction

of movement of the thread away from the bobbin will tend to release the end of the thread from the groove 16.

Obviously, the width of the various portions of the groove 16 as well as its depth will vary depending upon whether a thin or coarse thread is to be engaged therein.

Various other modifications and changes are likewise contemplated and may obviously be resorted to as only a preferred embodiment of the invention has been disclosed.

I claim as my invention:

1. A bobbin having a spindle provided with an annular groove, said groove having circumferentially spaced portions of different widths, adjacent the periphery of the spindle, and the depth of the groove being approximately as great as the widest part thereof.

2. A bobbin having a spindle provided with an

annular groove, the side walls of said groove being flared outwardly, and the inclination of said side walls varying at circumferentially spaced points.

5. A bobbin having a spindle provided with an annular outwardly opening groove, the sides of said groove, adjacent the periphery of the spindle, being flared outwardly relatively to one another, the inclination of said flared portions varying to provide circumferentially spaced flared portions of different inclinations.

10 4. A bobbin provided with a spindle, said spindle having an annular groove formed therein having circumferentially spaced portions, adjacent the periphery of the spindle, of different widths, and the bed portion of the groove being of substantially the same width throughout.

JOSEPH CAVANAUGH.
